BOX LOAD SUPPORT

Harold C. Pierce, Pomona, Calif.

Application July 25, 1947, Serial No. 763,691

10 Claims. (Cl. 105—369)

1

This invention relates generally to the bracing of boxed produce loads for shipment in refrigerator cars, and has to do particularly with an improved form of brace especially adapted for use in conjunction with the so-called "three high" citrus loads, i. e. car loads comprising two lower tiers of boxes stacked on end, and a top tier of boxes resting horizontally and in spaced relation transversely of the car.

One of my primary objects is to provide a new form of brace capable of maintaining the top box tier in the spaced and supported relation contemplated also by the type of brace disclosed in Patent No. 2,415,368, issued February 4, 1947, on "Boxed Produce Loads." Briefly, the specific form of the patented brace is that of a spacer member adapted to be placed horizontally between and in end engagement with the opposed faces of spaced pairs of boxes, the spacer member being contained within the space between the box rows and above the supporting boxes below, and having end projections received between engaged sides of the boxes.

In accordance with the invention, the brace unit is made in a form permitting its accommodation between boxes of the tier which supports the top boxes to be held in spaced relation, and having projections engageable with the opposed faces of the spaced boxes. As will appear, a single brace, or pair of braces, may be nailed or otherwise secured to the boxes below.

An additional object is to provide a brace adapted to formation from sheet metal stock by simple manufacturing processes permitting production of the braces in quantity and at low cost.

The various features and objects of the invention, as well as the details of certain illustrative embodiments, will be understood to better advantage from the following description of the accompanying drawing, in which:

Fig. 1 is a perspective view illustrating one form of the invention as applied to the spacing of boxes in the top tier of a so-called three high load;

Fig. 2 is an enlarged perspective view of the brace;

Fig. 3 is a view similar to Fig. 1 illustrating application to the box load of a variational form of the invention; and

Fig. 4 is an enlarged perspective view of the brace appearing in Fig. 3.

As will be understood by those familiar with produce loads, and particularly current types of citrus loads, the boxes are arranged within a refrigerator car as illustrated in Fig. 1, and in some-

2

what greater detail in the Pierce patent referred to above. For present purposes it will suffice to explain that in accordance with the so-called three high load, the general arrangement of which appears in Fig. 1, the crown packed boxes 10 are stacked on end within the car in two lower tiers 11 and 12 which support a top tier 13 in which the boxes are aligned with those in the lower tiers, but arranged top up with their long dimensions transversely of the car. Thus Fig. 1 is illustrative of a three high transverse row of vertically aligned boxes, it being understood that the car will contain a succession of such transverse rows with the boxes of successive rows in engagement 10 and the corresponding boxes in the successive stack rows aligned longitudinally of the car. Since the total long dimension of any number of the boxes is unequal to the car width, the top boxes in tier 13 in each stack row are spaced at 14 so that the end boxes 10a are maintained against the side walls of the car.

The invention is concerned with a novel form of spacer, generally indicated at 15 for positively maintaining the boxes spaced at 14 and against endwise shifting in the car. Referring to Fig. 2, the brace is made of sheet metal stock, either from separately formed sections 16 and 17 placed flatly in surface-to-surface engagement, or from a single stock piece, portions 16 and 17 of which are folded together at the lower edge 18. The brace comprises an elongated lower portion 19 containing a series of holes 20 through which nails may be driven into the boxes, and integral upstanding portions 21, the ends of which are bent outwardly in opposite directions and at right angles in the form of angular projections 22 having aligned straight edges 23.

After the stack row of Fig. 1 is loaded into the car, the brace 15 is applied to the forward surfaces of the boxes in the intermediate tier 12 below the box end 24 at the bottom of space 14. The brace is secured to the boxes by driving nails through openings 20, the nails serving to secure the brace against movement and interconnect the boxes into which the nails are driven. Projections 22 extend into the space 14 in engagement with the ends of the boxes defining the space, to positively maintain the boxes in the described spaced relation. After application of the brace, a corresponding and successive stack row is loaded into the car against the row of Fig. 1 to which the brace has been applied. Portion 19 of the brace is sufficiently thin to permit interengagement of the box surfaces between 50 which it is received, particularly when the boxes

are subjected to the usual load squeezing operation. The forwardly extending projections 22 then become received between the boxes of the subsequently loaded stack row, corresponding to the boxes defining the space 14, so that projections of a single brace engage and space apart the ends of two oppositely arranged pairs of boxes. The braces 15 may be inserted between successive transverse stack rows, or they may be used only between alternate rows in view of the capacity of a single brace to space the boxes in two adjacent rows.

Fig. 3 illustrates a variational embodiment of the invention applicable to the described form of load, and differing from the first form in that the brace is formed in separately applied sections. Referring to Fig. 4, each section 25 is made of double thickness sheet stock, drilled at 26 to receive the nails and having an upstanding portion 27 with its outwardly bent projections 28. As shown in Fig. 3 the brace sections are separately applied to the load by nailing their lower portions 25 to the intermediate box tier at locations such that the projections 28 engage the end faces of the top tier boxes to maintain the proper spacing at 14.

I claim:

1. A stabilized boxed produce load including oppositely positioned pairs of boxes spaced apart horizontally and supported on a lower tier of boxes vertically aligned with said pairs in one direction and presenting horizontal surfaces at the bottom of the space between them, and brace means for maintaining said pairs of boxes in spaced relation, said brace means comprising a pair of spaced box engaging elements each engaging one pair of boxes and downwardly offset means maintaining said elements in said spaced relation, said downwardly offset means being positioned between adjacent walls extending in said one direction of boxes in said lower tier.

2. A stabilized boxed produce load including oppositely positioned pairs of boxes spaced apart horizontally and supported on a lower tier of boxes vertically aligned with said pairs in one direction and presenting horizontal surfaces at the bottom of the space between them, and brace means for maintaining said pairs of boxes in spaced relation, said brace means comprising a pair of spaced box engaging elements each engaging one pair of boxes and downwardly offset means maintaining said elements in said spaced relation, said downwardly offset means extending in said one direction between adjacent walls of boxes in said lower tier, said offset means being sufficiently thin to permit interengagement of the box walls between which they are positioned.

3. A stabilized boxed produce load including oppositely positioned pairs of boxes spaced apart horizontally and supported on a lower tier of boxes vertically aligned with said pairs in one direction and presenting horizontal surfaces at the bottom of the space between them, brace means for maintaining said pairs of boxes in spaced relation, said brace means comprising a pair of spaced box engaging elements each engaging one pair of boxes and downwardly offset means maintaining said elements in said spaced relation, said downwardly offset means extending in said one direction between adjacent walls of boxes in said lower tier, and means securing said downwardly offset means against vertical movement relative to the boxes in said lower tier.

4. A stabilized boxed produce load including oppositely positioned pairs of boxes spaced apart

horizontally and supported on a lower tier of boxes vertically aligned with said pairs in one direction and presenting horizontal surfaces at the bottom of the space between them, and a one-piece thin metallic brace having a pair of spaced box engaging elements and a downwardly offset portion connecting said elements and extending in said one direction between interengaged walls of boxes in said lower tier, said box engaging elements each presenting a pair of horizontally turned metallic projections engaging one pair of said boxes.

5. For use in stabilizing boxed produce loads including oppositely positioned pairs of boxes spaced apart horizontally, brace means to be carried by the box load for maintaining said pairs of boxes in spaced relation, said brace means comprising a pair of spaced box engaging elements each adapted to engage one pair of boxes, and downwardly offset means for maintaining said elements in said spaced relation adapted to be positioned in the vertical plane of the adjacent walls of said pairs of boxes beneath the level of said boxes.

6. For use in stabilizing boxed produce loads including oppositely positioned pairs of boxes spaced apart horizontally, brace means to be carried by the box load for maintaining said pairs of boxes in spaced relation, said brace means comprising a pair of upstanding spaced box engaging elements each adapted to engage one pair of boxes, and a downwardly offset portion extending between and connecting said upstanding elements and adapted to be positioned in the vertical plane of the adjacent walls of said pairs of boxes directly beneath the space between said pairs of boxes.

7. For use in stabilizing boxed produce loads including oppositely positioned pairs of boxes spaced apart horizontally, brace means to be carried by the box load for maintaining said pairs of boxes in spaced relation, said brace means comprising a pair of upstanding spaced box engaging elements each adapted to engage one pair of boxes, and each having a downwardly offset portion for positioning said element relative to the load and adapted to be positioned in the vertical plane of the adjacent walls of said pairs of boxes beneath the level of said boxes.

8. For use in stabilizing boxed produce loads including oppositely positioned pairs of boxes spaced apart horizontally, a thin sheet metal brace for maintaining said pairs of boxes in spaced relation, said brace comprising a pair of spaced parallel upstanding portions and a downwardly offset portion extending between and connecting said upstanding portions, said upstanding and downwardly offset portions lying in a common plane for positioning in the vertical plane of the adjacent walls of said pairs of boxes, each of said upstanding portions of the brace having a pair of oppositely and laterally turned projections at its upper end for engaging one pair of said boxes, said downwardly offset portion of the brace being adapted for positioning beneath the level of said boxes.

9. For use in stabilizing boxed produce loads including oppositely positioned pairs of boxes spaced apart horizontally, a thin sheet metal brace for maintaining said pairs of boxes in spaced relation, said brace comprising a pair of spaced parallel upstanding portions and a downwardly offset portion extending between and connecting said upstanding portions, said upstanding and downwardly offset portions lying

in a common plane for positioning in the vertical plane of the adjacent walls of said pairs of boxes, each of said upstanding portions of the brace having a pair of oppositely and laterally turned projections at its upper end for engaging one pair of said boxes, said downwardly offset portion of the brace being adapted for positioning beneath the level of said boxes and containing openings for reception of fasteners to mount the brace to a lower tier of boxes.

10. For use in stabilizing boxed produce loads including oppositely positioned pairs of boxes spaced apart horizontally, a pair of thin sheet metal braces to be carried by the box load for maintaining said pairs of boxes in spaced relation, each of said braces comprising an upstanding portion and a downwardly offset horizontally extending portion, said portions lying in a com-

mon plane for positioning in the vertical plane of the adjacent walls of said pairs of boxes, said upstanding portions of the braces each having a pair of oppositely and laterally turned projections at its upper end for engaging one pair of said boxes, said downwardly offset portions of the braces being adapted for positioning beneath the level of said boxes and being adapted for attachment to a lower tier of boxes.
